UNITED STATES PATENT OFFICE.

EDMUND HOFFMAN, OF NEW YORK, N. Y., ASSIGNOR TO AMERICAN STOPPER COMPANY,
A CORPORATION OF NEW JERSEY.

JAR AND BOTTLE CLOSURE.

942,141.

Specification of Letters Patent. Patented Dec. 7, 1909.

Application filed January 5, 1908. Serial No. 470,748.

To all whom it may concern:

Be it known that I, EDMUND HOFFMAN, a citizen of the United States, and a resident of the city of New York, county of Kings, 5 and State of New York, have invented certain new and useful Improvements in Jar and Bottle Closures, of which the following is a specification.

The object of my invention is to provide an 10 efficient jar closure in which a practical seal will be provided, and in which the cost of producing will be very much below that of jar seals of this kind now in use.

Prior to my invention, so far as I am 15 aware, jar and bottle closures or seals embodying threads or projections formed on the jar neck and coöperating projections on the cap have been employed in various forms, and the caps have been made of various 20 materials. In all cases where metal has been employed for making the cap, in order that its coöperating projections be strong enough to resist the internal pressure exerted against the cap and the stresses due to 25 the engagement of the cap and jar, the cap has been made of very strong metal. Strength in this regard has almost invariably been provided by using heavy or thick metal. In none of these structures was the 30 spring of the metal utilized to insure the retention of the cap on the jar. By reason of the thickness of the metal employed, and the shape of the coöperating parts on the cap and jar, this was not feasible.

35 My invention, primarily, involves the idea of using very thin metal for the cap, to the end that the cost of production of the closure may be materially reduced, and incidentally, to provide a seal wherein the en- 40 gaging projection of the cap is supported when the cap is sealed to the jar by an abutment on the jar conforming to the shape or inclination of the projection on the cap, to the end that the spring of the metal may be 45 availed of to clench the cap to the jar while the abutment gives support to the metal preventing it from being distorted by the presence of internal pressure against the cap, the spring clenching or locking the cap to the 50 jar so that it will not become inadvertently dislodged, but which will permit it to be readily removed when required. So far as the idea of the coöperating cap projection

and jar abutment are concerned, it is not essential that the cap be made of metal, as the 55 benefits of my invention in this regard may be measurably realized by making the cap of material which has no inherent spring. This and other objects are accomplished by my invention, one embodiment of which is 60 described below.

For a more particular description of my invention, reference is to be had to the accompanying drawings forming part hereof, 65 in which:

Figure 1 is a side elevation of a jar provided with my improved cap. Fig. 2 is a similar view with the cap removed. Fig. 3 is a plan view of the structure shown in Fig. 2. Fig. 4 is a sectional view taken on the 70 line 4—4 of Fig. 1, looking in the direction of the arrows. Fig. 5 is a sectional view taken on the line 5—5 of Fig. 1, looking in the direction of the arrows. Fig. 6 is an enlarged elevation of a portion of a cap provided with my improvements; and Fig. 7 is an inverted plan view of the same. Figs. 8 and 9 are sectional views taken on the lines 75 8—8 and 9—9 respectively, of Fig. 7, looking in the direction of the arrows. 80

Throughout the various views of the drawings, similar reference characters designate similar parts.

In the embodiment of my invention as disclosed herein, at 1 is shown my improved 85 cap and at 2 my improved bottle or jar. The coöperating elements on the jar comprise angular or bayonet-joint like grooves 3 having lower wall 4 inclined at an angle which may be about 60° to a plane parallel 90 to the top of the jar. The upper wall 5 of each of these grooves 3 has its lower edge converging toward the inner end 5^a of the groove for a portion of its length, the terminal of the groove having the edges of both 95 its walls parallel as at 5^b, Fig. 2. The cap which is conventionally formed, except for my improvements, comprises the top 6 and a pendent annular flange 8. The cap is provided with a packing 7 of suitable material. The cap may be also provided with projections 9 to enable the cap to be turned readily 100 by hand, but these are not essential and may be omitted, and any other form of projections may be employed. In the embodiment 105 shown herein, four grooves 3 are employed,

but the number is not essential. I have shown four elements on the cap adapted to engage the jar elements, but it is apparent that the number may be modified to suit 5 particular requirements.

To provide means for coöperating with the groove 3, I form, at stated intervals on the flange 8, the inwardly extending and upwardly inclined lugs 10. These are preferably formed in the cap by a circular die, but they may be formed in any other desired way. The angle of inclination of the lugs correspond with that of the wall 4 of the groove 3, as clearly shown in Fig. 5. I also 15 prefer to form the upper edge 10^a slightly inclined.

The operation is substantially as follows: Each of the lugs 10 is inserted in the mouth 20 of the groove 3 until the inclined surface of the lug appears on the inclined surface of the wall 4 of the groove. The cap is then turned until the lug passes beyond the mouth, at which time its inclined edge engages with the inclined wall 5 of the groove.

25 A continuation of this turning movement slightly springs the metal of the lug so as to increase its frictional contact with the jar, and a continuation of the movement brings the lug into the contracted terminal 5^a of the groove. During this entire turning movement each lug has been supported by the inclined wall 4 of the groove and when the lug is turned home into the terminal 5^a, the upper edge of the lug will be somewhat 30 sprung and will engage the upper wall 5^b of the terminal so that the lug will be firmly supported below by an inclined abutment, its metal slightly sprung and held with firm frictional contact against the upper wall 5^b 35 of the terminal of the groove. It will be clear from the foregoing that should the stresses due to placing the cap on the jar, which is very often done initially by machinery, tend to bend the metal of the lugs 40 they will be supported by the inclined abutment at all times; and that when pressure is brought against the cap from inside the jar the spring of the metal in the lugs can be availed of, at the same time the bending of 45 50 the same to such an extent as to unseal the cap will be effectively prevented by the support which the abutment gives to the lug; and the combination of the slightly resilient lug with the contracted terminal of the jar 55 grooves, the inclined lug and inclined abutment further clenches or locks the cap on the jar so as to effectively prevent inadvertent displacement of the cap, at the same time

permitting the same to be turned with comparative ease to remove the cap from the jar. 60

From the foregoing it will be apparent that my invention can be embodied in forms other than those disclosed herein, coming within the purview of the annexed claims.

Having described my invention, I claim: 65

1. The combination of a jar and a cap having an annular pendent flange and means for attaching the cap and jar together comprising an inwardly and upwardly inclined lug on the cap flange and a groove on the jar 70 having an inwardly and upwardly inclined abutment for coöperation with said lug.

2. The combination of a jar having a plurality of grooves formed in its upper edge, each groove comprising an enlarged opening, a gradually contracting extension from the opening and a lower and upwardly inclined wall, and a cap having a pendent annular flange and a coöperating series of inwardly and upwardly extending lugs adapted to be entered into said grooves and engage the same. 75

3. The combination with a jar having grooves formed in its exterior with inclined lower walls and gradually decreasing in diameter, of a cap having a pendent annular flange, inwardly and upwardly inclined lugs formed in the flange, with the angle of inclination corresponding with that of the lower wall of the grooves and bearing thereagainst, 90 the upper edge of said lugs being inclined to the horizontal. 85

4. In a device of the class described, a jar or bottle neck having bayonet-joint like grooves with inclined lower edges. 95

5. In a device of the class described, a bottle neck having bayonet-joint like grooves with inclined lower edges, and a cap with lugs struck therefrom having surfaces adapted to engage said bevel edges and force the top of said lugs against the upper wall of 100 said bayonet-joint like grooves.

6. In a device of the class described, a bottle neck having bayonet-joint like grooves with inclined lower edges, and a sheet metal 105 cap having lugs struck therefrom adapted to enter said grooves and having surfaces engaging said inclined lower edges and thereby forcing the upper edges of said lugs against the upper walls of said grooves. 110

Signed at the city of New York, county of New York, this 4th day of January, 1909.

EDMUND HOFFMAN.
